WALL RADIO FOR CUSTOM INSTALLATION OR SIMILAR ARTICLE

Edward E. Shaffer, Columbus, Ohio, assignor to Shaffer Music Company, Columbus, Ohio, a corporation of Ohio

Application February 21, 1955, Serial No. 34,623

Term of patent 14 years

(Cl. D26—14)

Figure 1 is a front elevational view of a wall radio for custom installation or similar article, showing my new design; and Figure 2 is a side elevational view thereof. The dominant features of my new design are shown in solid lines in the drawing.

I claim:

The ornamental design for a wall radio for custom installation or similar article, as shown and described.
